UNITED STATES PATENT OFFICE.

WALTER O. AMSLER, OF PITTSBURGH, PENNSYLVANIA.

ANNEALING FURNACE OR LEER.

Application filed May 21, 1920. Serial No. 383,256.

To all whom it may concern:

Be it known that I, WALTER O. AMSLER, a citizen of the United States, residing at Pittsburgh, in the county of Allegheny and ⁵⁵ State of Pennsylvania, have invented certain new and useful Improvements in Annealing Furnaces or Leers, of which the following is a specification.

The present invention relates to annealing ¹⁰ furnaces or leers of the continuous type, and particularly to glass leers in which a furnace of great length is employed, as distinguished from annealing furnaces having a short fire box or heating chamber. In a companion ¹⁵ application Serial No. 264,491, filed November 29, 1918, I have shown and described an annealing furnace of the type to which the present invention relates, and have incorporated in this application many of the features shown in the said companion case.

Among the objects of my invention are, to provide a furnace and a tunnel in communication therewith of great length, in combination with a plurality of overhead ²⁵ independent combustion chambers; means for passing products of combustion and heating gases into the tunnel structure for the purpose of heating the entrance of the tunnel and its forward end for a considerable distance; means for passing the products of combustion, etc., into the tunnel structure and returning them to the chimney; and new and improved means for effecting a ³⁰ desired temperature control throughout the length of the annealing chamber and the tunnel.

In the accompanying drawings, which illustrate an application of my invention,

Figs. 1 and 2 are longitudinal sectional ⁴⁰ views showing respectively the annealing furnace construction and the tunnel construction embodying my invention;

Fig. 3, a horizontal sectional view showing one-half of the furnace construction and ⁴⁵ one-half of a portion of the tunnel construction; and

Fig. 4, a vertical sectional view taken on line 4—4 of Fig. 1.

Referring to the drawings, 2 designates ⁵⁰ the side walls of the furnace, 3 and 4 front and rear walls, and 5 the arched top. These elements are of the usual brickwork con-

struction, and are disposed on a suitable foundation 6. The furnace illustrated is of the continuous type, and communicates ⁵⁵ at one end through an opening 7 in the rear wall 4 with a tunnel 8.

It will be noted that I employ a furnace of considerably more length than the usual and well known furnaces of the class to ⁶⁰ which my invention relates, and that I also provide a muffle or an annealing chamber of great length, whereby I am enabled, in conjunction with the combination and arrangement of parts hereinafter described, to effect ⁶⁵ a highly efficient temperature control, thereby making it possible for the material to be treated under very favorable conditions.

The muffle or annealing chamber 9 has its side walls constructed of tiles 10 and blocks ⁷⁰ or tiles 11, its arch of tiles 12, and its bottom or floor of tiles 13. Forming the side walls of two tiles, that is to say, the side wall tile proper 10 and the skew tile or block 11, and resting the arch on the skew ⁷⁵ blocks, as shown, provides a highly satisfactory construction, preventing cracks developing in the tiles, and preventing products of combustion from entering the muffle.

As illustrated and as preferred, I employ ⁸⁰ two combustion chambers 14 and 15, said chambers being located between the top of the annealing chamber and the under side of the roof of the furnace. 16 and 17 designate laterally extending partition walls ⁸⁵ separating the combustion chambers, and 18 designates a similar wall located adjacent the chimney 19. As shown, I provide two burner structures 20 for each combustion chamber. I find that by providing two ⁹⁰ or more burners for each combustion chamber, I am enabled to better control the temperature within the annealing chamber.

Interposed between the side walls of the annealing chamber and the side walls of the ⁹⁵ furnace, I provide a series of vertically extending flues 21 designed for passing products of combustion and gases from the combustion chambers down into flues located under the floor 13 of the annealing chamber. ¹⁰⁰ Similar flues are also provided for connecting the space or compartment 22 disposed beyond the combustion chambers, thus permitting the passage of gases from the flues

below the floor 13, upwardly into chamber 22, and thence downwardly therefrom into the said flues located below the floor of the annealing chamber.

5 23 designates a laterally extending partition wall disposed under the floor 13 and designed to cause the products of combustion and heating gases to be passed upwardly from the said under flues to the chamber 22.

The side flues 21 are provided with dampers 24 adapted to be operated from the outside of the furnace. By means of these dampers, it will, of course, be evident that 15 I can control the passage of products of combustion through the side flues 21, and consequently, conveniently regulate the temperature within the annealing chamber.

20 The construction and arrangement of the flues below the floor 13 of the annealing chamber and the bottom or floor 13^a of the furnace, which flues connect with the side flues 21, vary somewhat, the arrangement and construction of the said flues being particularly shown by Fig. 3. As shown therein, I provide a plurality of longitudinally extending flues 25 extending from the front of the furnace to the laterally extending partition wall 23. Under the forward portion of the annealing chamber it is desirable to pass the products of combustion and heating gases directly to the center of the bottom of the annealing chamber, and I have therefore provided laterally extending flues 26, said flues connecting with the longitudinally extending flues 25.

Under the second combustion chamber, instead of passing the gases directly to the middle of the under side of the annealing 40 chamber, the gases are passed laterally through short flues 27 and then backwardly by means of the flues 28, the latter communicating with the longitudinally extending flues 25.

45 The arrangement of the flues under the rear portion of chamber 22 is similar to the flue construction under the first combustion chamber. That is to say, I employ laterally extending flues 29 whereby the heating gases are directed outwardly into longitudinally extending flues 25^a.

The longitudinally extending flues 25^a extend beyond the chimney 19 and into the front portion of the tunnel 8, and for this purpose, the floor 13 as well as floor or bottom 13^a is carried for a considerable distance into the tunnel structure. By means of the flue construction just described, I cause the heating gases to travel for a considerable distance within the tunnel structure. Said gases travel under the tunnel up to the wall 30 and are then returned to the chimney by means of flues or passages 31. While the longitudinally extending flues 25 and 25^a are separated by the wall 23, they are in effect

continuous flues for conveying the products of combustion and the heating gases back through the furnace and into the tunnel.

The ware or materials to be annealed are passed through the annealing chamber and 70 the tunnel by means of a conveyor 32, said conveyor, as illustrated, being mounted on drive wheels 33 and 34 respectively located at the end of the tunnel and at the forward end of the annealing chamber or furnace. 75 35 designates a motor for driving the conveyor and as shown the motor is connected with the drive wheel 33 by means of a drive chain 36.

80 While I have shown the chimney located between the tunnel and the furnace proper, it will be evident that the chimney may be otherwise located so long as means are provided for passing the heating gases into or 85 under the tunnel, and conveying the said gases from the tunnel structure to the chimney.

It will be understood that the products of combustion and the heating gases, after their travel under the annealing chamber will, 90 owing to the wall 23, be caused to pass upwardly into chamber or compartment 22, and from said chamber downwardly into the longitudinally extending flues by which they 95 are conveyed to the tunnel.

What I claim is:

1. In an annealing furnace or leer, an annealing chamber, a tunnel in communication therewith, a combustion chamber at the exterior of the annealing chamber, a longitudinally extending flue in communication with the combustion chamber and arranged to convey gases therefrom, said flue extending along the forward end of the tunnel for 100 heating it.

2. In an annealing furnace or leer, an annealing chamber, a tunnel in communication therewith, a combustion chamber, a longitudinally extending flue disposed under the 110 floor of the annealing chamber and communicating with the combustion chamber, said flue arranged to convey heated gases therefrom and extending along the forward end of the tunnel for conveying heating gases 115 thereto.

3. In an annealing furnace or leer, an annealing chamber, a tunnel in communication therewith, a combustion chamber, and flues in communication with the combustion chamber, through passages at the exterior of the annealing chamber and extending along the outside of the tunnel for heating the forward end of the tunnel.

4. In an annealing furnace or leer, an annealing chamber, a combustion chamber located over the top of the annealing chamber, longitudinally extending flues under the annealing chamber, side flues about the exterior of the annealing chamber connecting 125 the combustion chamber with the longitudi- 130

nally extending flues, and a tunnel in communication with the annealing chamber, said longitudinally extending flues extending along a portion of the tunnel for heating it.

5. In an annealing furnace or leer, an annealing chamber, a tunnel in communication with the annealing chamber, a chimney disposed between the annealing chamber and tunnel, longitudinally extending heating flues disposed below the annealing chamber and extending beyond the chimney and under the tunnel, and a passage at the side of the longitudinally extending 10 flue communicating with the rear end thereof for conveying gases back to the chimney.

6. In an annealing furnace or leer, an annealing chamber, a tunnel in communication with the annealing chamber, a chimney disposed between the annealing chamber and tunnel, and longitudinally extending heating flues disposed below the annealing chamber and extending beyond the chimney and into the tunnel structure and 20 exteriorly of the tunnel, said flues having connections with the chimney and arranged to produce a flow of gases from the tunnel back to the chimney.

7. In an annealing furnace or leer, an annealing chamber, a tunnel in communication with the annealing chamber, a chimney disposed between the annealing chamber and the tunnel, a combustion chamber disposed over the top of the annealing chamber, vertically extending side flues, and longitudinally extending heating flues disposed below the annealing chamber and extending beyond the chimney and into the tunnel structure.

40 8. In an annealing furnace or leer of the continuous type, an annealing chamber, a tunnel in communication with the annealing chamber, a chimney disposed between the annealing chamber and tunnel, a plurality of combustion chambers disposed over 45 the top of the annealing chamber, vertically extending side and longitudinally extending bottom heating flues, said longitudinally extending heating flues extending beyond the chimney and along the forward end of the tunnel.

9. An annealing furnace or leer comprising an annealing chamber, a tunnel forming an extension of the annealing chamber, a combustion chamber at the exterior of the annealing chamber, flues surrounding the annealing chamber and communicating with the combustion chamber for circulating

gases around the annealing chamber, said flues extending rearwardly along the outside of the tunnel for heating the forward end of the tunnel.

10. An annealing furnace or leer comprising an annealing chamber, a tunnel forming an extension of the annealing chamber, a combustion chamber at the exterior of a portion of the annealing chamber, flues communicating with the combustion chamber and arranged to pass the heated gases around the top, bottom and sides of the annealing 60 chamber, said flues extending rearwardly under the forward end of the tunnel, whereby the forward portion of the tunnel is heated by the partially cooled gases.

11. An annealing furnace or leer comprising an annealing chamber, a tunnel forming an extension of the annealing chamber, a combustion chamber at the exterior of the forward end of the annealing chamber, a second combustion chamber at the exterior 65 of the annealing chamber and disposed rearwardly of the first combustion chamber, a main flue common to both combustion chambers which communicates therewith through flues passing around the annealing 70 chamber, said main flue being arranged to circulate the heated gases of combustion around and under the remaining portion of the annealing chamber and extending rearwardly outside the forward end of the tunnel, whereby the forward end of the tunnel 75 is heated by the partially cooled gases.

12. An annealing furnace or leer comprising an annealing chamber, a tunnel extending rearwardly from the annealing chamber, a combustion chamber at the top of the forward end of the annealing chamber and exteriorly thereof, a longitudinally extending flue under the annealing chamber and forward end of the tunnel, vertical flues 80 communicating with the longitudinal flue and combustion chamber, passages at the sides and top of the rear portion of the annealing chamber, and baffle walls so arranged in the longitudinal flue and in the 85 passages that the heated gases of combustion will travel around the bottom, top and sides of the annealing chamber and under the forward end of the tunnel.

In testimony whereof I affix my signature 90 in presence of two witnesses.
